UNITED STATES PATENT OFFICE.

LEON J. WICKERSHAM, OF COLUMBUS, OHIO.

DESIGN FOR A RESILIENT TIRE.

Application filed February 10, 1926. Serial No. 16,470. Term of patent 14 years.

To all whom it may concern:

Be it known that I, LEON J. WICKERSHAM, a citizen of the United States, residing at Columbus, in the county of Franklin and State of Ohio, have invented a new, original, and ornamental Design for Resilient Tires, of which the following is a specification, reference being had to the accompanying drawings, forming a part thereof.

In the drawings:

Figure 1 is a fragmentary, perspective view of a tire casing provided with the tread of the invention; and

Figure 2 is a cross-section of the tire.

I claim:

The ornamental design for a resilient tire, as shown.

LEON J. WICKERSHAM.
